United States Patent Office

Des. 180,862

Patented Aug. 27, 1957

180,862

WASHING MACHINE OR THE LIKE

Carl H. Clement, Jr., Perrysburg, Ohio, assignor to Bock
Laundry Machine Company, Toledo, Ohio, a corporation of Ohio

Application January 9, 1957, Serial No. 44,454

Term of patent 14 years

(Cl. D49—1)

Fig. 1 is a front perspective view of a washing machine or the like, showing my new design;

Fig. 2 is a top plan view thereof;

Fig. 3 is a rear perspective view thereof, and

Fig. 4 is a side perspective view thereof.

I claim:

The ornamental design for a washing machine or the like, substantially as shown.
